HEATING APPARATUS

Walter S. Landon, Detroit, Mich., assignor to Detroit Lubricator Company, Detroit, Mich., a corporation of Michigan

Application March 5, 1940, Serial No. 322,414

15 Claims. (Cl. 236—9)

My invention relates generally to heating apparatus and more particularly to apparatus for controlling the flow of liquid fuel to a hydroxylation type oil burner.

An object of this invention is to provide a control apparatus for modulating the output of the fuel burner.

A further object is to provide a control apparatus which upon failure will prevent a dangerous burner operation.

A further object is to provide an apparatus which acts to provide natural draft flow of air to the burner upon failure of the forced air supplying means.

A further object is to provide means for interconnecting the air controlling means with the fuel controlling means to provide at all times the correct proportion of fuel and air to the burner.

The invention consists in the novel arrangement and construction of the parts to be more fully described hereinafter and the novelty of which will be particularly pointed out and distinctly claimed.

In the accompanying drawings, to be taken as a part of this specification, I have fully and clearly illustrated a preferred embodiment of my invention, in which drawings:

Figure 1 is a schematic view of a heating system employing a liquid fuel burner and showing my control apparatus and the control system therefor;

Fig. 2 is a top plan view of the control apparatus with certain of the parts removed in order to show more clearly a portion of the controlling means and showing a simplified control circuit therefor;

Fig. 3 is a front view in elevation of the apparatus with a portion of the fuel controlling means in vertical section;

Fig. 4 is a view substantially along the line 4—4 of Fig. 2 looking in the direction of the arrows;

Fig. 5 is a view substantially along the line 5—5 of Fig. 2 looking in the direction of the arrows;

Fig. 6 is a schematic view of a modified form of a heating system showing my burner control apparatus in conjunction with a modified fluid control system;

Fig. 7 is a view in central vertical section of the space temperature sensitive element of Fig. 6 and showing the adjusting means;

Fig. 8 is a view of the modified control apparatus of Fig. 6 taken in central vertical section through the control chamber, the fuel chamber and the power element and also a view showing in elevation the control system bulb means;

Fig. 9 is a top plan view of a modified form of the controlling apparatus;

Fig. 10 is a view substantially along the line

10—10 of Fig. 9 looking in the direction of the arrows and with the fuel chamber partly broken away and partly shown in section, and

Fig. 11 is a view substantially along the line 11—11 of Fig. 9 looking in the direction of the arrows with the control chamber and fuel chamber removed but showing the air supplying means connected thereto.

Referring to the drawings by characters of reference, the numeral 1 indicates generally a heating apparatus for a hydroxylation type burner 2 to be supplied by fuel and air through conduits 2^a and 2^b respectively, leading from a control device 3. The products of combustion from the burner 2 pass upwardly into the combustion chamber 4 and outwardly therefrom through a central aperture 4^a of the chamber 4 and pass downwardly between the outer wall of the combustion chamber 4 and a shell 5 which separates the products of combustion from but transfers the heat to the air within a plenum chamber 6. The spent combustion products then pass to atmosphere through a stack 6^a which is controlled by means of a damper 6^b. A constantly operating air circulating fan 7 is driven by an electric motor 8, connected thereto by means of a pulley and belt drive 9 and extracts air from the space 10 to be heated through an outlet duct means 11 which leads to a fan inlet chamber 12. Air is forced outwardly by the fan 7 through a duct 13 into the furnace plenum chamber 6 where it is heated due to its contact with the heated furnace shell 5 and flows therefrom through a duct 16 to the space 10.

The operation of the burner 2 is controlled by means of a unique room thermostat, diagrammatically shown at 17, and described in detail hereinafter. The thermostat 17 acts to maintain a predetermined temperature within the space 10. Excess heating of the plenum chamber 6 is prevented by means of the usual high temperature limit control 18 which acts to reduce the fuel flow to the burner 2 upon occurrence of a predetermined high temperature in the chamber 6 to prevent overheating thereof. Fuel oil is stored in an oil tank 19, and flows therefrom through a conduit 19^a, and through a constant level device 19^b, and through the conduit 20, to the control means 3. The fuel oil is metered by the control means 3 and flows therefrom through the conduit 2^a to the fire pot 21. The necessary air for combustion of the fuel oil is supplied by the fan 7 and flows through a conduit 22 which opens into the duct 13 through an orifice 23 and leads to the control means 3 where the air is regulated in proportion to the quantity of fuel oil being supplied to the burner. The regulated air then flows through the air conduit 2^b to the burner 2 where it combines with the fuel oil to form a highly efficient combustible mixture.

Positioned in one wall of the conduit 22 is an air pressure regulator or shutter 24 which acts to maintain a substantially constant air pressure within the conduit 22 at all times. Should the pressure within the conduit begin to exceed the predetermined desired pressure, the shutter 24 will open to allow the excess air to escape and should the pressure begin to decrease below atmospheric pressure, the shutter 24 will open to allow atmospheric pressure within the conduit 22.

The control means 3 preferably comprises a chambered housing or hollow casing member 25 having a chamber 26, with an inlet 27 connected to the conduit 22, and an outlet 28 connected with the conduit 2^b (see Fig. 1). Flow through the chamber 26 is controlled by a plate-like shutter 29 positioned within the chamber 26. The top portion of the shutter 29 is rigidly secured to a shaft 29^a, spaced from but positioned adjacent the top wall of the chamber 26 and which is journaled at either end in opposite end walls 30, 31 of the chamber 26. The shutter 29 when inert hangs downward across the inlet 27 and normally acts to close the inlet 27 to flow of air but is urged in an open direction (see Fig. 5) by the pressure of the air within the conduit 22. The shutter 29 preferably has a large aperture 32 there-through. A pair of ears 33 (only one of which is shown) are bent toward the inlet 27 from the shutter 29, one adjacent each of the aperture 32 side edges and both adjacent the aperture 32 bottom edge. The ears 33 have aligned apertures therein for receiving a shaft 34. A second plate-like shutter 35 overlies the aperture 32 of the shutter 29 on the inlet 27 side thereof and has a pair of ears 36 projecting from its side edges and adjacent its bottom edge (only one of which is shown). The ears 36 have aligned apertures through which the shaft 34 extends so that the shutter 35 is pivotally carried by the shutter 29. A bolt-like threaded member 37 is secured to the shutter 35 adjacent its upper edge portion and extends toward the inlet 27. A nut-like weight member 38 is threaded on member 37 and biases the shutter 35 in an opening direction to open the aperture 32 for flow of air. The member 38 may be moved back and forth to determine the biasing of the shutter 35. The shutter 35 is held in its position against the shutter 29 by the pressure of the air within the conduit 22. Should the air pressure fall below a predetermined minimum, the weight member 38 will pivot the shutter 35 about the shaft 34 to open the aperture 32 for free flow of air. Upon reduction of the air pressure within conduit 22 to atmospheric pressure, the shutter 24 will open and air under natural draft will flow from atmosphere through the conduit 22, through the chamber 26, and through the conduit 2^b to the burner 2.

The housing member 25 has a second chamber 39 located adjacent the chamber 26 and which is separated therefrom by the wall 30. The chamber 39 has an open top wall 40, a bottom wall 41, and side walls 42, 43, 44 in addition to the common wall 30. The chamber 39 is supplied with fuel oil by the conduit 20 which is connected to a chamber inlet 45 opening through the side wall 42, adjacent the bottom wall 41. The chamber 39 has an outlet 46 positioned in and extending from the bottom wall 41 for connection with the conduit 2^a. Flow through the outlet 46 is controlled by means of a valve member 47 which cooperates with a valve port 48 in the outlet 46. The valve member 47 has an extending valve stem portion 49 which projects upwardly through the chamber 39 substantially parallel to the side walls

thereof. Substantially midway between the bottom wall 41 and the top wall 40, the side walls 30, 42, 43 and 44 have an upwardly facing shoulder 50 against which is positioned a plate-like member 51. The member 51 has an aperture through which the valve stem portion 49 projects and in which the valve member 47 is guided in its reciprocal movement. The side walls 30, 42, 43 and 44 also have a second upwardly facing shoulder 52 positioned below the top wall 40 and above the shoulder 50 and against which is positioned a plate-like member 53. The member 53 is apertured to receive and guide a reduced stem portion 54 of the valve stem portion 49. The plate-like members 51, 53 cooperate to divide the chamber 39 into a plurality of smaller chambers 55, 56 and 57, chamber 55 being the bottom or fuel oil chamber, chamber 56 being the intermediate or power element chamber, and chamber 57 being the top or adjustment chamber. The valve stem portion 49 is drilled concentrically with its longitudinal axes to form a passageway 58 which opens at its lower end below the valve port 48 and connects at its upper end with a radially drilled hole 59 which communicates with the upper portion of the chamber 55, above the substantially constant fuel level maintained therein by the constant level device 19^b. A passageway 60, in a boss integral with the wall 43, has its lower end opening into the outlet 46 and its upper end opening through the shoulder 50 in alignment with an aperture through the member 51. The member 53 has an aperture or drilled hole 61 there-through for maintaining the chamber 56 at atmospheric pressure. The passageways 58, 60 and drilled holes 59, 61 cooperate together to form a vent for the space within chamber 55 overlying the liquid and also a vent for the outlet 46 so that the outlet on the conduit 2^a side of the valve port 48 will always be maintained at atmospheric pressure. By maintaining atmospheric pressure in chamber 55 and in conduit 2^a any relative variations in height between the control device 3 and the burner 2 does not affect the fuel flow through the valve port 48. The plate-like member 53 has a pair of threaded apertures in which are threaded secured a pair of adjustably threaded stop members 64, 65 respectively. The stop members 64, 65 have at their lower end portions, flanges 66, 67 which cooperate respectively with upper and lower surfaces of an annular flange 68 of the reduced stem portion 54 to limit opening and closing movement of the valve member 47. The stop member 65 may be set for any fuel flow which will burn with natural draft or air supplied at atmospheric pressure to the burner 2. It must be remembered, however, that the stop member 65 adjusts the minimum burner operation and the burner 2 will therefore never operate to supply less heat even though the thermostat 17 be in a satisfied position. The stop member 65 therefore should be properly adjusted so that when the burner 2 is operating at minimum flow conditions it will not overheat the space 10.

65 The shaft 29^a has a portion 69 which extends into the chamber 39 and more particularly into the power element chamber 56. The extending portion has rigidly secured thereto one end of a crank arm 70 which terminates in an end portion 71. The side wall 44 is slotted, as at 71^a, to provide clearance for the arm 70. A boss 72 projects from the wall 30 into the power element chamber 56 and adjacent the wall 42. A fulcrum pin 73 is rotatably carried within an aperture extending through the boss 72 and the wall 30 and

has an end portion within the chamber 26 peened to prevent its removal from the aperture in one direction and has an end portion within the chamber 56 which has secured thereto one pivoted end portion 74 of a second degree lever member 75. The member 75 extends toward the wall 44 substantially parallel to the wall 30 and terminates in a bifurcated end portion 76 which receives the end portion 71 of the crank arm 70 carried by the shaft 29^a. A circular portion of the lever member 75 is positioned intermediate the bifurcated end portion 76 and the pivoted end portion 74 and is positioned between the annular flange 68 and a second flange 77 which, like annular flange 68, extends outwardly from the reduced stem portion 54 of the valve member 47 and which is spaced from and below the annular flange 68.

Positioned in the chamber 56 and secured to the side wall 42 thereof is one end of a supporting member 78 which carries at its other end the bimetallic element 79. The bimetallic element 79 is hook-shaped and has a cylindrical portion 80 with a longitudinally split side wall. One edge portion 81 of the split is secured to the supporting member 78 and the other edge portion has a radially outwardly extending lip 82. An electrical heater means 83 is positioned within the portion 80 in heat exchange relation therewith and acts upon energization thereof to heat the portion 80 so that it tends to open up and to raise the lip 82. The lip 82 normally engages the upper face of a shoulder 84 formed on the valve stem portion 49 at the intersection of the normal diameter portion with the reduced diameter portion and limits upward movement of the valve member 47. The heater means 83 is preferably of large mass so that it has a slow rate of temperature change and acts to heat the portion 80, in response to the average time the heater means is energized, rather than being responsive to heat the portion only when the heater means is actually energized. The heater means 83 has lead wires 85, 85^a which extend therefrom and terminate at binding posts 86, 87 which are carried by a terminal block 88. The block 88 is mounted, as by screws, to the outside of the wall 42 and spaced therefrom by a spacer means 89.

Air pressure in the inlet 27 acts on the shutters 29, 35 to rotate the shaft 29^a in a clockwise direction (see Fig. 4). Clockwise movement of the shaft 29^a acts through the crank arm 70 to rotate the lever member 75 in a counter-clockwise direction. Rotation of the lever member 75 in the counter-clockwise direction acts to move the valve member 47 upward from the valve port 48 to allow greater flow of fluid from the chamber 55 to the burner 2. Upward movement of the valve member 47 is limited by engagement of the shoulder 84 with the lip 82, and the lip 82 acts as a variable stop to limit the flow of fuel oil and air to the burner in accordance with the temperature of the space 10 as reflected by the thermostat 17.

The room thermostat 17 comprises a bimetallic responsive blade 90 which carries a contact member 91 cooperable with a fixed contact member 92 to control an electric circuit in response to changes in temperature of the blade 90. Electrical energy from a suitable source of supply is conducted to the primary terminals of a transformer 93 by means of lead wires 94. The transformer 93 has a secondary coil terminating in terminals 95, 96. Lead wires 97 are directly connected to the lead wires 94 and to the electric motor 8 so that the motor 8 is supplied with electrical energy for continuous operation. The

bimetallic blade 90 is connected by means of a lead wire 98 to one terminal 95 of the transformer 93. The fixed contact member 92 is connected, by means of a lead wire 99, to one binding post 86 of the control device 3. The other binding post 87 of the control device 3 is connected by means of a lead wire 100 to one side of the limit switch 18 which has its temperature sensitive element located within and sensitive to the temperatures of air in the plenum chamber 6. The other terminal of the limit switch 18 is connected by means of a lead wire 101 to the terminal 96 of the transformer 93. The thermostat 17 also includes a resistance heater element 102 which acts upon energization to heat the bimetallic blade 90 to cause the contact members 91, 92 to separate and break the electrical circuit controlled thereby. The heater element 102, unlike the heater means 83, is one having a small mass so that it is quickly heated and cooled and heats the blade 90 more nearly in direct accordance to its energization or at a given predetermined rate. One terminal of the heater 102 is directly connected to the contact member 92 and the other terminal of the heater 102 is connected by means of a lead wire 103 to the terminal 96 of the transformer 93. The thermostat 17 is preferably so constructed that the bimetallic blade 90 is operable to close the contact members 91, 92 at a minimum predetermined temperature and to open the contact members 91, 92 at a maximum predetermined temperature and the difference between the maximum predetermined temperature and the minimum predetermined temperature is the differential temperature of the thermostat 17. The heater 102 is so chosen that it will act upon continuous energization to heat the bimetallic blade 90 to a predetermined temperature above the surrounding air temperature and which predetermined temperature is greater than the differential temperature of the thermostat 17. Due to the effect of the heater 102, the blade 90 is made to part the contact members 91, 92 in a cycling manner until the temperature of the surrounding air reaches or exceeds the minimum predetermined temperature at which the blade 90 will move the contact members 91, 92 into circuit closed position. By so constructing and arranging the heater 102, the heater means 83 and the blade 90; the thermostat acts in effect to modulate the flow of fuel and air to the burner in accordance with the heating requirement thereof.

The operation of the burner apparatus may best be seen by giving an example. Assume that the cut-in or the minimum predetermined temperature at which the blade 90 moves contact members 91, 92 together is 70° F. and the cut-out or the maximum predetermined temperature at which the blade 90 moves contact members 91, 92 apart is 72° F. The differential of operation is therefore 2° F. The heater 102 is so positioned and arranged relative to blade 90 that it will raise the temperature thereof the entire 2° F. in five minutes. Thus when the space 10 temperature lowers to 70° F. the blade 90 closes contact members 91, 92 energizing heater 102 and heater means 83. Without rise in the temperature of the space 10, the heater 102 would act, at the end of five minutes, to part the contact members 91, 92 and with temperature rise in space 10, the time would be somewhat shortened. In the five minutes or less interim, however, the heater means 83 will have increased somewhat in temperature and heated the portion 80 of the element 79,

This heating will cause the lip 82 to move upward slightly so that the air pressure in the conduit 22 will act to move the shutters 29, 35 to allow an increased flow of air to the burner. Movement of the shutter 29 acts through shaft 29^a, crank arm 70 and lever member 75 to open the valve member 47 in proportion to the rate of increase in the supplied air. The lip 82, however, still continues to act as a stop and limits the increased flow in proportion to the heating effect imparted to the cylindrical portion 80 by the heater means 83.

Returning again to the action of the thermostat, the contact members 91, 92, having deenergized the circuit to the heater 102, the blade 90 cools rapidly, say in five minutes, and the blade 90 is again subject to the temperature of the space 10. If the heating effect of the burner 2 was sufficient to raise the space 10 temperature above 70° F., the contact members 91, 92 remain parted. If, however, not enough heat has been supplied, the contact members 91, 92 will be moved together again by the blade 90 and the heater means will be given again a period of heating. If the space temperature dropped to say 67° F. and the heater 102 was designed to raise the temperature of the blade only 4° F. on continuous energization, the blade would be maintained at 71° F. and the heater means 83 would remain constantly energized so that after a given time the lip 82 of element 79 will raise and allow the air pressure within conduit 22 to move the shutters 29, 35 and valve member 47 until the flange 68 engages the flange 66 of the stop member 64 at which time the burner is operating at maximum flow capacity. Under the cycling conditions, however, the heater means 83 is getting little "bumps" of heat and maintains an average temperature intermediate the maximum temperature and that of the surrounding media. After a prolonged period of deenergization, however, the heater means 83 will cool and the lip 82 will lower to move the valve member 47 until the flange 68 engages the flange 67 of the stop member 65 at which time the burner 2 is operating at minimum fire condition.

Should, however, the air pressure fail within the conduit 22 for any reason such as plugging of the orifice 23 or failure of the fan 7, the shutter 35 will fall forward due to the biasing effect of the weight member 38 to open the aperture 32 and the shutter 24 will open so that air under natural draft will flow to the burner 2. As the air pressure acting on the shutters 29, 35 is the sole means of opening the valve member 47, the valve member 47 will remain against the minimum fire stop member 65 irrespective of the heating of the element 79 by the heater means 83. There is, therefore, no danger of the burner 2 being flooded with fuel oil and burning with a sooty flame or of causing an explosion. It may therefore be seen that the burner apparatus is operable to modulate the heating effect in accordance to the demand by the space to be heated; will accurately proportion the relative amounts of air and fuel to maintain at all times the proper fuel-air mixture; requires no additional fan motor for supplying the burner; and will automatically go to minimum flow natural draft conditions upon failure of the air pressure.

The circuit which is shown in Fig. 2 is diagrammatically that which is shown in Fig. 1 with the exception that the limit control has been omitted.

Figs. 6, 7 and 8 show a modified form of the

control system in which a fluid control has been used in place of the electrical control. For simplicity a natural convection heating furnace has been shown but this fluid control could be used in a forced convection heating installation with equal ease and, if so used, the air circulating fan could be used to furnish air to the burner, as in Fig. 1, instead of a fan means 105 as shown. The parts of Figs. 6, 7 and 8, which are substantially the same as the parts in the preceding figures, are designated by the same reference characters.

In keeping with the showing of a natural convection heating system, the outlet duct means 11 of the space 10 is connected directly to the plenum chamber 6 in place of the duct 13. The fan means 105 supplies air under constant pressure through a duct means 106 to the inlet 21 of the control device 3. The control device 3 is operated by the fluid control system which comprises a thermostat 107 positioned in and sensitive to the temperature within the space 10, a pressure sensitive power element 108 operatively connected to the control device 3 and a pressure generating bulb means 109 which is positioned in heat exchange relation with the bottom wall 110 of the fuel burner fire pot 21. The thermostat 107, element 108, and means 109 are communicatively connected together by a conduit means 111.

The thermostat 107 comprises a cylindrical casing including a chamber 112 having a side wall 113, and a lower end wall or bottom wall 115. The bottom wall 115 has an aperture therethrough in which is sealed in fluid-tight relation one open end portion of the conduit means 111 for communication with the chamber 112. The side wall 113 has an aperture 116 therethrough and the side wall 113 has a boss 117 projecting inwardly into the chamber 112 diametrically opposite and in alignment with the aperture 116. A bellows member 118 has one end portion secured in fluid-tight relation, as at 119, to the wall 113 around the peripheral edge of the aperture 116. The other end of the bellows member 118 projects within the chamber 112 and is sealed in fluid-tight relation to an end member 120. A closure member 121 overlies the aperture 116 and is held in fluid-tight relationship to the exterior surface of the wall 113 by solder 121a.

The bellows member 118 and end member 120 cooperate to make the chamber 112 a variable volume receptacle communicating with the conduit means 111 through the bottom wall 115. The volume of the chamber 112 is controlled by means of an adjustment screw 122 which is threadedly received in an aperture through the closure member 121. The screw 122 has a head portion 123 external of the closure member 121 which may be manually gripped for rotation of the screw 122 to adjust the volume of chamber 112. If desired, an indicator may be secured to the screw 122 and suitable indicia carried by the wall 113 to indicate the setting of the screw 122. The other end 124 of the screw 122 extends within a space 125 defined by the bellows member 118, closure member 121, and end member 120. The end 124 is rounded and engages the end member 120 to hold it against movement due to the compression force of a helical coil compression spring 126 which is held under compression between the wall 113 and end member 120. The spring 126 has its end portions surrounding and held in position by the boss 117 and a boss 127 on the end member 120. The spring 126 acts to maintain the end member 120 at all times in engagement with the end 124, and

needs to exert a greater force than the innate resilient force of the bellows member 118 so that as the screw 122 is moved inward into the space 125, the bellows 118 will expand and upon outward movement of the screw 122 the bellows will compress.

A second portion of the conduit means 111 is sealed in fluid-tight relation to an aperture in the bottom wall of a cup-shaped casing 128 of the power element 108 and is in communication with the interior thereof. The power element 108 comprises the casing 128 which has an out-turned flange portion 129 secured to the wall 42 of the control device 3, a bellows member 130 and a thrust member 131. One end portion of the bellows member 130 is sealed in fluid-tight relationship to the inner peripheral edge of an annular ring member 132 which has its outer periphery sealed in fluid-tight relationship to the inner wall of the cup-shaped casing 128 adjacent the open end thereof. The other end of the bellows member 130 extends inwardly into the casing 128 toward the bottom wall thereof and is sealed in fluid-tight relationship to an end member 133. The casing 128, bellows member 130, end member 133 and ring member 132 cooperate to form a sealed pressure responsive chamber 134. The thrust member 131 comprises a cylindrical member 135 having a concentric bore 136 therethrough. A portion 137 of the bore 136 is of enlarged diameter and opens through one end of the member 135. A rod-like thrust member 137^a is reciprocal within and fits within the bore 136 and has one end portion extending beyond the member 135 and secured to the end member 133. The other end of the rod-like member 137^a extends into the enlarged diameter bore portion 137 and has a head portion 138 which is operable to reciprocate within the portion 137 but is urged against a shoulder formed at the intersection of the enlarged diameter bore portion 137 and the normal diameter of the bore 136 by a helical-coil compression spring 139, which spring 139 is also positioned within the bore portion 137.

The spring 139 is held under compression and against the head portion 138 by an abutment member 140 threaded into the open end of the enlarged diameter bore portion 137. A conical end portion 141 of the member 140 extends beyond the cylindrical member 135 and is received within a conical recess 142 of a vertically extending arm 143 of a bell-crank lever member 144 pivoted, as at 145, to a boss 146 which extends outwardly from the chamber wall 30. The horizontal arm 147 of the bell-crank lever member 144 abuts the upper face of the shoulder 84 of the valve member 47 and acts to limit upward movement thereof similarly to the lip 82 of the bimetallic element (shown in Fig. 4). The spring 139 holds the head portion 138 against the shoulder with a force greater than any normal force exerted by the power element 108 so that normally the thrust member 131 acts as a rigid member but which upon abnormal pressure exerted by the power element 108 acts to collapse to relieve the pressure within the chamber 134 without a corresponding movement of the lever member 144. The power element 108 also includes a helical coil compression spring 148 positioned within the bellows member 130 surrounding and concentric with the member 131. One end of the spring 148 abuts the end member 133 and its other end abuts the outer surface of the wall 42. The spring 148 acts to oppose collapsing movement of the bellows member 130 in its move-

ment of the valve member 47 toward closed position.

A third portion of the conduit means 111 is communicatively connected to the bulb means 109 and which bulb means acts to provide the pressure for the control system. The bulb means 109 is positioned within a well 149 of a heat conducting member 149^a which has a portion secured in heat exchange relation with the bottom wall 110 of the fire pot 21.

The chamber 112, power element 108 and the conduit means 111 is at all times maintained substantially completely filled with a temperature sensitive volatile liquid, the pressure of which is controlled by the bulb means 109 as will be described hereinafter. There being substantially no flow through the system the vapor pressure is transmitted undiminished by means of the liquid to the pressure responsive chamber 134 of the power element 108 and to the chamber 112. Increase in pressure in the chamber 134 acts to move the end member 133 with a consequent increase of force exerted by the spring 148 and increase in the opening force of the valve member 47 acting through the bell-crank member 144. This is true because of the rate of increase in force exerted by this spring 148 and the increase in valve opening force exerted by the air pressure within the inlet 27 of the control device 3 as the shutters 29, 35 approach closed position, additional pressure in bulb means 109 is necessary as the valve member 47 approaches minimum flow condition. It will also be noted that as the bellow 130 collapses, the chamber 134 increases in volume which will tend to allow fluid to escape from the bulb means 109 to decrease the pressure therein. The final system pressure and position of the power element 108 will be a position of equalization of pressure within the means 109 and element 108.

The operation of the control system is as follows: As the liquid within chamber 112 increases in volume with increase in its temperature due to increasing temperature within the space 10, a quantity of the liquid is forced from the conduit means 111 into the bulb means 109 where it is vaporized by the heat conducted to the bulb means 109 through the member 149^a. This will increase the pressure within the bulb means 109 and be transmitted to the liquid in the conduit means 111 and chambers 112 and 134. Increased pressure within the chamber 134 causes the end member 133 to compress the spring 148 to move the thrust member 131 to rotate the bell-crank member 144 in a clockwise direction (see Fig. 8) until a balance of force again occurs as was set forth hereinbefore. Additional rise in temperature of the liquid within chamber 112 causes additional liquid to be ejected from the conduit means 111 into the bulb means 109 to increase the pressure acting on the liquid in the conduit means 111 and chambers 112, 134.

Upon cooling of the chamber 112 liquid is received therein from the conduit means 111 which allows fluid to escape from the bulb means 109 thereby lowering the pressure within the bulb means 109 and the chambers 112, 134 so that the shutters 29, 35 and the valve member 47 can open. The expansion and contraction of the liquid in the chamber 112 is very gradual and continuous and it, therefore, may readily be seen that the valve member 47 will be modulated throughout its range of movement to decrease and increase the output of burner 2 in response to change in temperature of the space 10.

Should the adjustment screw 122 be rotated manually throughout its range in a temperature lowering direction, considerable liquid will be ejected from the conduit means 111 into the bulb means 109 due to the decrease in volume of chamber 112. Because of the large amount of liquid ejected into the means 109 and the restricted rate of flow of heat to the bulb means 109 through the member 149^a it will take considerable time to vaporize the liquid to increase the pressure enough to move the valve member 47 and shutters 29, 35 to closed position. This lag should preferably be sufficiently great so that the valve member 47 and shutters 29, 35 will slowly move toward closed position possibly taking two minutes or longer thereby to prevent a smoky flame which results from immediately stopping the flow of air before the fuel pool in the pot 21 is consumed.

The operation of the apparatus shown in Figs. 6, 7 and 8 is substantially the same as explained in respect to the preceding figures except for the change in the air supplying means, and the control system, as set forth hereinbefore, and a further description is deemed unnecessary.

In Figs. 9, 10 and 11 there is shown a modification of my device in which the mechanical interconnection between the air controlling means and the fuel controlling means is maintained but instead of the continuously throttling type of fuel control there is shown an apparatus which modulates the output in steps. A chambered casing 150 has an upper or control chamber 151, a lower or constant level fuel oil chamber 152 positioned below the control chamber 151 and an air flow passageway or chamber 153 which is positioned above the constant level chamber 152 and beside of the chamber 151, with a wall 154 in common with the chamber 151. A plate-like supporting member 155 for the modified control apparatus, to be hereinafter described, is positioned within the chamber 151 and has a plurality of upturned flanges or supporting portions 156, 157 from its side edges and has flange portions 158, 159 extending upwardly from its end edge portions. The flange portions 156, 157 are respectively secured to the protuberances 160, 161 projecting inwardly from side walls 162, 163 of the chamber 151 by suitable means, such as screws. The end flange portion 159 is suitably secured to the common wall 154 and holds the bottom portion 164 of the plate-like supporting member 155 in a substantially horizontal position parallel to a bottom wall 165 of the chamber 151. The wall 154 and end flanges 158, 159 have aligned apertures in which a shaft 166 is journaled for rotational movement. A portion 167 of the shaft 166 extends into the chamber or air flow passageway 153 and rigidly carries a cam member 168 for cooperation with one face of a butterfly damper or shutter 169, pivoted at its upper edge portion, as at 170, to the top wall 171 of the chamber 153. The shutter 169 is biased toward open position by a helical coil tension spring 172 which has one end rigidly secured, as at 173, to the top chamber wall 171 of the chamber 153 and which has its other end secured, as at 174, to the face of the shutter 169 opposite to that engaged by the cam member 168. The chamber 153 has open end walls 175, 176 and the open end 176 is connected to the inlet side of a fan or air supply means 178 which is used to supply air to the fuel burning apparatus, such as the fuel burner 2 (shown in Fig. 1). The open end wall 175 may be opened to and subjected to atmospheric pressure so that when the fan means 178 is in op-

eration the atmospheric pressure acts on the shutter 169 and urges it against the force of the helical coil spring 172 toward closed position. Referring again to the chamber 151 and the plate-like supporting member 155, it will be seen that the bottom portion 164 has a pair of upturned fingers 179, 180 which carry a medium fire and a high fire bimetallic power element 181, 182 respectively and which elements are preferably hook-shaped in form and have cylindrical portions 183, 184 respectively. The portions 183, 184 are longitudinally split to form side wall end portions 185, 186 and 187, 188 respectively. Lip or power transmitting portions 187^a, 188^a, respectively, extend radially outward from portions 187, 188. The end portions 185, 186 are secured to the fingers 179, 180 and support the bimetallic power elements 181, 182 rigidly with the member 155.

A valve member 189, positioned within chamber 152, controls flow of fuel therefrom through an outlet 190 which is adapted to be connected to the conduit 2^a for controlling the flow of fuel-oil to the burner 2. The valve member 189 has a stem portion 191 which projects upwardly from the chamber 152 through an aperture in the bottom wall 165 into the chamber 151 and terminates in a reduced diameter end portion 192. This portion 192 is guided for reciprocal movement within an aperture extending through a protuberance or boss 193 projecting inwardly from the side wall 162. The reduced diameter end portion 192 has a pair of spaced annular outwardly extending flanges 194, 195. Screw-threaded within apertures in the protuberance 193 are a pair of stop members 196, 197 having flanges 198 (only one of which is shown) which cooperate with the under and upper surface of the flange 194 to limit reciprocal movement of the valve member 189 and controls the minimum and maximum flow of fuel oil to the burner 2. A third stop member 199 is threadedly secured to a plate-like member 200 which is secured by means of a screw to a protuberance 201 which projects inwardly within the chamber 151 from the wall 154. The lip portion 187^a upon its upward movement engages the stop member 199 which limits the upward movement of portion 187 and its lip portion 187^a to determine the intermediate fire operation. The high fire bimetallic element 182 is operatively connected to the shaft 166 for movement thereby in one direction by a lever member 202 rigidly secured to the shaft 166 and which has an extending arm portion 203 operable to engage the upper surface of the element lip portion 188^a. A second lever member 204 is pivotally connected to the shaft 166 and has an arm portion 205 which is received intermediate the flanges 194, 195 and has a second portion 205^a which overlies a portion 205^b of the lever member 202. The lever member 204 is connected to the lever member 202 by an adjustment mechanism comprising a threaded screw 206 which is loosely received within an aperture in the lever member portion 205^a and is threaded within an aperture in lever member portion 205^b. A helical coil compression spring 207 surrounds the screw 206 and is placed under compression between the lever member portions 205^a, 205^b and acts to urge the lever member portion 205^a against the head of the screw 206. The bimetallic power elements 181, 182 are actuated by a pair of electric heating units 208, 209 positioned within the cylindrical portions 183, 184 respectively, of the bimetallic elements 181, 182. The units 208, 209 act to heat

the bimetallic elements so that the portions 183, 184 will open up thereby moving the lip portions 187^a, 188^a in an upward direction. Upon upward movement of the lip portion 187^a it engages the underside of the flange 195 to lift the valve member in an opening direction and is limited in its movement by the engagement of the lip portion 187 with the lower end of the stop member 199. Upward movement of the valve member, due to the positioning of the arm portion 205 of lever member 204 between the flanges 194, 195, acts to rotate the lever member in a clockwise direction (see Fig. 11) and the cam member 168 to coact with the face of the shutter 169 to force the shutter 169 against the air pressure in the passageway 153 to allow flow of air therethrough to the inlet of the fan means 178. By correctly proportioning the cam surface and the valve member 189, the relative flows of oil and air may be accurately controlled so that the correct proportion of each for proper combustion may be admitted to the fuel burner 2. Upon energization, the heating unit 209, which is the high fire heater, acts to heat the cylindrical portion 184 so that the lip portion 188^a moves upward to engage the arm portion 203 of the lever member 202 to rotate the shaft 166 further in a clockwise direction. Further movement of the shaft 166 causes the shutter 169 to move to a further open position, and causes the valve member 189 to move to a further open position to supply additional fuel corresponding to the additional air supplied to the fuel burner 2. The flange 195 will, under high fire conditions, be spaced above the lip portion 187^a.

The heating units 208, 209 are electrically connected in the following manner: The unit 208 is connected by means of lead wires 210, 211 to binding posts 212, 213 respectively carried by a terminal strip 214 secured in a suitable manner externally of the chamber 151 to the side wall 163 and the unit 209 is connected by means of lead wires 215, 216 to the binding post 213 and to a binding post 217 respectively, the binding post 217 being carried by the terminal strip 214. A transformer 218 has its primary coil connected by means of lead wires 219 to a source of electrical energy and has its secondary coil 220 connected to terminals 221, 222. A lead wire 223 connects the terminal 222 to the binding post 213 so that one side of the heaters 208, 209 are connected directly to one side of the transformer secondary coil 220. The other terminal 221 of the transformer 218 is connected by means of a lead wire 224 to a thermostat, diagrammatically shown at 225, and which may be positioned within the space heated by the burner 2. The thermostat 225 comprises a bimetallic blade 226 which is directly connected to the lead wire 224, and which carries a pair of contact members 227, 228, the contact member 227 being secured to the blade by a spring member 227^a and the contact member 228 being directly secured thereto. The members 227, 228 cooperate respectively with a pair of stationary contact members 229, 230. The contact members 227, 229 act to complete an electric circuit at a higher blade temperature than the blade temperature necessary to close the contact members 228, 230. The contact member 229 is connected by means of a lead wire 231 to the binding post 212 and the contact member 230 is connected by means of a lead wire 232 to the binding post 217.

The operation of the modification in Figs. 9, 10 and 11 is as follows: The fan means 178 is

continually operating and the suction created thereby causes the atmospheric pressure to act on the shutter 169 to hold it in engagement with the cam member 168. If the thermostat 225 is satisfied or in open circuit condition, as shown, the shutter will be in nearly closed position, as shown in Fig. 11. Upon a decrease in temperature in the space and of the blade 226, the contact members 227, 229 will be moved into engagement. This closes an electrical circuit from the terminal 221, lead wire 224, blade 226, contact members 227, 229, lead wire 231, binding post 212, lead wire 210, heating unit 208, lead wire 211, binding post 213 and lead wire 223 to the terminal 222. Upon closure of this circuit the heating unit 208 heats the cylindrical portion 183 and the lip portion 187^a will move upwardly lifting the valve member 189 until the lip portion 187^a engages the stop member 199 which limits the opening movement. Upward movement of the valve member 189 acts through lever member 204 to rotate the shaft 166 and cam member 168 to move the shutter 169 against the force of the atmospheric pressure to allow for increased air flow to the burner 2 in proportion to the increased fuel oil flow. Should the burner output not be sufficient to maintain the space temperature and the temperature should fall to a predetermined lower temperature, the contact members 228, 230 will engage. This energizes a second circuit from the terminal 221 through lead wire 224, blade 226, contact members 228, 230, lead wire 232, binding post 217, lead wire 216, heating unit 209, lead wire 215, binding post 213, and lead wire 223 to the terminal 222. Energization of the heating unit 209 acts to heat the cylindrical portion 184 and thereby to move the lip portion 188^a upward to engage the arm portion 203. Continued upward movement of the portion 188^a acts to move the lever member 202 to rotate the shaft 166. Rotation of the shaft acts through the arm portion 205 to lift the valve member until the flange 194 engages the stop flange 198 of the stop member 197 to limit its upward movement and which also limits rotation of the shaft. Rotation of the shaft also acts to move the cam member 168 to move the shutter 169 in a further open direction to allow additional air to flow to the burner 2 to maintain the proper fuel-air mixture in accordance with the increased flow of fuel oil.

Upon opening of either of the sets of contact members 228, 230 or 227, 229, the connected heating units 209, or 208 respectively, will cool along with the cylindrical portions 184 or 183 so that the air pressure acting on the shutter 169 will act through the cam member 168 to rotate the shaft 166 in a counterclockwise direction (see Fig. 11) thereby moving the shutter 169 and moving the valve member 189 toward closed position. It will, therefore, be seen that in the modified form of the apparatus the power elements act to open the valve and acts as a stop to limit closing movement of the valve member and shutter by the air pressure in the chamber 153.

In case of failure of the air supplying means 178 the pressure across the shutter 169 will decrease and the spring 172 will move the shutter 169 to open position to allow natural draft to the burner 2.

What I claim and desire to secure by Letters Patent of the United States is:

1. In an oil burning apparatus, a liquid fuel burner, means for controlling flow of fuel to

said burner, means for supplying air under pressure to said burner, air pressure positioned damper means for controlling the flow of air to said burner from said supplying means, lever means mechanically interconnecting said fuel controlling means and said air controlling means, automatic means operable to control the positions of both said fuel controlling means and said air controlling means solely when said air supplying means is effective thereby to maintain efficient operation of said burner, and means operable independently of said automatic means for rendering said air controlling means ineffective to control the flow of air upon failure of said air supplying means.

2. In an apparatus of the character described, a fluid fuel controlling means, an air flow controlling means, a shaft member, means interconnecting said fuel means and said shaft means, an abutment member connecting said shaft means and said air means, said air means being so positioned and related to the air pressure that said air means is held thereby against said abutment member, and means acting to urge said air means out of engagement with said abutment member and operable upon a predetermined low pressure of the air controlled by said air means.

3. In an apparatus of the character described, a fluid fuel controlling means, an air flow controlling means, a shaft means, means interconnecting said fuel means and said shaft means, an abutment member connecting said shaft means and said air means, said air means being so positioned and related to the air pressure that said air means is held thereby against said abutment member, means acting to urge said air means out of engagement with said abutment member and operable upon a predetermined low pressure of the air controlled by said air means, and power means acting on said fuel means to move said fuel means and said air means against the force of the air pressure.

4. In a device of the character described, a fuel supply chamber having an inlet and an outlet, a control chamber positioned above said supply chamber, a valve member controlling flow through said outlet and having a portion extending upwardly through said fuel chamber into said control chamber, an air controlling means, mechanical means interconnecting said valve member and said air means, a heat actuated thermostatic element positioned within said control chamber and operable to move said air controlling means in one direction, a heat actuated means within said control chamber, and lever means actuated by said heat actuated means and operable through said connecting means to move said air controlling means further in said one direction.

5. In a device of the character described, a fuel supply chamber having an inlet and an outlet, a control chamber positioned above said supply chamber, a valve member controlling flow through said outlet and having a portion extending upwardly through said fuel chamber into said control chamber, an air controlling means, mechanical means interconnecting said valve member and said air means, a heat actuated thermostatic element positioned within said control chamber and operable to move said air controlling means in one direction, a heat actuated means within said control chamber, lever means actuated by said heat actuated means and operable through said connecting means to move said air controlling means fur-

ther in said one direction, and means responsive to a condition of the air to render said heat actuated means ineffective to move said air controlling means.

6. In a liquid fuel burner control apparatus, a constant level liquid fuel chamber having an outlet and having an inlet, a control chamber, a fuel valve controlling flow through said outlet and having a stem portion and having a projecting portion, stop means engageable by said projecting portion for limiting movement of said valve in an opening direction, air controlling means for regulating the flow of air to the burner, mechanical means operable to control said air means and interconnecting said valve and said air means, said mechanical means being operable upon movement in one direction to move said valve in a closing direction, power means limiting movement of said mechanical means in said one direction, a heat actuated power element, and a lever member moved by said power element and operable to limit movement of said mechanical means in said one direction, said power element being operable through said lever member and said mechanical means to control said air means.

7. In a liquid flow burner control apparatus, a constant level liquid fuel chamber having an outlet and having an inlet, a control chamber overlying said fuel chamber, a fuel valve controlling flow through said outlet and having a stem portion extending into said control chamber and having a projecting portion, stop means engageable by said projecting portion for limiting movement of said valve in an opening direction, air controlling means for regulating the flow of air to the burner, mechanical means operable to control said air means and interconnecting said valve and said air means, said mechanical means including a lever member, said lever member being operable upon movement in one direction to move said valve in a closing direction, heat actuated power means limiting movement of said lever member in said one direction, stop means engageable by said power means to limit movement thereof upon energization, a heat actuated power element, a lever member moved by said power element and operable to limit movement of said first-named lever member in said one direction, said power element being operable through said second-named lever member and said mechanical means to control said air means, and means operable upon a condition corresponding to lack of air to render said power element ineffective to control said air means.

8. In a burner system for heating a space, a fuel control valve, means for moving said valve toward open position, a first fluid container positioned within and responsive to the temperature of the space, a second fluid container positioned in thermal relation with and responsive to the temperature of the burner, a pressure sensitive means having an operating element, means connecting said containers and said sensitive means to form a sealed interconnected system, a temperature sensitive volatile fluid within said system, said fluid being so related to said system that said connecting means and said first container and said pressure means are substantially completely filled with liquid at all times, said fluid which is in said second container being so related thereto that all of said fluid may be in a vaporous state, the pressure of said vaporous fluid acting to determine the pressure of said

fluid within said system, and means operatively connecting said operating element and said valve to limit movement thereof by said moving means in accordance with the pressure of said fluid within said second container.

9. In a burner system for heating a space, a fuel control valve, means for moving said valve toward open position, a first fluid container positioned within and responsive to the temperature of the space, a second fluid container, means having a predetermined rate of heat transfer for transmitting heat from the burner to said second container, a pressure sensitive means having an operating element, means connecting said containers and said sensitive means to form a sealed interconnected system, a temperature sensitive volatile fluid within said system, said fluid being so related to said system that said connecting means and said first container and said pressure means are substantially completely filled with liquid at all times, said fluid which is in said second container being so related thereto that all of said fluid may be in a vaporous state, the pressure of said vaporous fluid acting to determine the pressure of said fluid within said system, and means operatively connecting said operating element and said valve to limit movement thereof by said moving means in accordance with the pressure of said fluid within said second container.

10. In a burner system for heating a space, a fuel control valve, means for moving said valve toward open position, a first fluid container positioned within and responsive to the temperature of the space, a second fluid container positioned in thermal relation with and responsive to the temperature of the burner, a pressure sensitive means having an operating element, means connecting said containers and said sensitive means to form a sealed interconnected system, a temperature sensitive volatile fluid within said system, said fluid being so related to said system that said connecting means and said first container and said pressure means are substantially completely filled with liquid at all times, said fluid which is in said second container being so related thereto that all of said fluid may be in a vaporous state, the pressure of said vaporous fluid acting to determine the pressure of said fluid within said system, means operatively connecting said operating element and said valve to limit movement thereof by said moving means in accordance with the pressure of said fluid within said second container, and means operable upon a predetermined abnormal pressure within said system to reduce said abnormal pressure.

11. In a fluid fuel control apparatus, a fluid fuel burner, means for controlling flow of fluid to said burner, means for supplying oxygen under pressure to said burner, means for controlling the flow of oxygen and operable to exert a force proportional to the pressure of the oxygen, mechanical force transmitting means interconnecting said fuel controlling means and said oxygen controlling means and operable to maintain predetermined relative movement therebetween for proportioning the relative flow of the oxygen and flow of the fuel, said force transmitting means being operable to transmit the force of said oxygen controlling means to said fuel controlling means, means sensitive to the output of said burner and operable to regulate the move-

ment of said fuel controlling means against the force exerted by said pressure responsive oxygen controlling means, and means for rendering said sensitive means ineffective to actuate one of said controlling means upon a predetermined reduction in pressure of the oxygen available in said supplying means.

12. In an apparatus of the character described, in combination a fuel flow controlling valve and an air flow controlling valve, means for establishing a pressure differential across said air controlling valve, means interconnecting said valves and operable to provide predetermined relative movement therebetween, means for moving said valves toward open position, and means operable upon a predetermined reduction in said pressure differential for rendering said interconnecting means ineffective to maintain said predetermined relative movement.

13. In an oil burner control apparatus, a duct for flow of air to the burner, a pressure responsive air valve having an opening therethrough, a pivoted valve plate closing said opening and movable to open position upon reduction of air pressure, said valve regulating the supply of air to the burner and eccentrically mounted within said duct to be urged toward open position due to the force of the air impinging thereon, means controlling flow of fuel to the burner, means interconnecting said air valve and said fuel controlling means so that movement of said air valve to supply more air to the burner acts to move said fuel controlling means to supply more fuel to the burner, and thermostatic means actuated in accordance with the output of the burner and mechanically cooperating with said fuel means to determine the position to which said fuel means is movable by said air valve.

14. A fluid fuel burner control device comprising a casing having a passageway therethrough for flow of fluid fuel and having a passageway therethrough for flow of combustion supporting air, means for propelling air through said air passageway, a reciprocal fuel valve in said fuel passageway, an air valve responsive to air pressure and controlling air flow through said air passage, automatic means actuated in accordance with temperature change and operable to control the opening movement of said fuel valve, and means relating the position to which said air valve is moved by air pressure to the position to which said fuel valve is movable under the control of said automatic means.

15. A fluid fuel burner control device comprising a casing having a passageway therethrough for flow of fluid fuel and having a passageway therethrough for flow of combustion supporting air, means for propelling air through said air passageway, a reciprocal fuel valve in said fuel passageway, an air valve responsive to air pressure and controlling air flow through said air passage, automatic means actuated in accordance with temperature change and operable to control the opening movement of said fuel valve, means relating the position to which said air valve is moved by air pressure to the position to which said fuel valve is movable under the control of said automatic means, and means cooperable with said air valve to establish an open air flow path through said air passageway upon failure of said propelling means.
